UNITED STATES PATENT OFFICE.

FRANK S. LIPPITT, OF CLEVELAND, OHIO.

FRESH-AIR-SUPPLY DEVICE.

937,827.

Specification of Letters Patent. Patented Oct. 26, 1909.

Application filed August 3, 1906. Serial No. 329,092.

To all whom it may concern:

Be it known that I, FRANK S. LIPPITT, a citizen of the United States, resident of Cleveland, county of Cuyahoga and State 5 of Ohio, have invented a new and useful Improvement in Fresh-Air-Supply Devices, of which the following is a specification, the principle of the invention being herein explained and the best mode in which I 10 have contemplated applying that principle, so as to distinguish it from other inventions.

My invention relates to means for supplying fresh air to patients in hospitals and sick rooms. As will be obvious it is equally 15 well adapted, when desired, for use in the sleeping apartments of well persons.

The object of my invention is to provide means of the character indicated that will be neat in appearance and convenient in 20 their manner of attachment and use, and that, furthermore, will insure not only access of the outside air to the person using the same but a continuous circulation of such air by or over him if required.

25 Said invention consists of means herein-after fully described and specifically set forth in the claims.

The annexed drawing and the following description set forth in detail certain means 30 embodying the invention, such disclosed means constituting but one of various mechanical forms in which the principle of the invention may be used.

In said annexed drawing: Figure 1 represents a front elevation of my device, showing the same attached to a window of a 35 sleeping room and properly positioned for use over a bed; Fig. 2 is a plan view of such device; and Fig. 3 is a side elevation as viewed from the left in Fig. 1.

As will appear from an inspection of such figures my invention, as embodied in the form there shown, comprises first of all a canopy or inclosure A that hangs loosely 45 over the head end of the bed, being conveniently supported at D against the frame E of such bed. An approved construction of this canopy is to make a substantially rectangular frame over which cloth of a suitable 50 quality is stretched so as to entirely inclose the sides and top of such frame except as hereinafter specified. Since the bottom of the frame should rest but loosely on upper portion of the bed, in order not to 55 discommode the patient, the cloth covering

of the frame should be provided with a ruffle or apron as shown to prevent unnecessary escape of outside air into the room. This cloth covering is detachably secured to the frame, which latter for the sake of lightness is made of wire or similar material, and may hence be removed whenever necessary for laundering. To permit the patient to look without the canopy it is desirable to provide a window K, preferably of flexible 60 material, in the front of canopy, such window being merely laced or otherwise detachably secured to the canopy side in order that it may be readily removed when the canopy is being laundered. To provide for the free 65 access of pure outside air to the patient, which is the desideratum here sought to be accomplished, the canopy A, as thus described, is connected by a suitable duct or passage, or a plurality of ducts or passages 70 with the exterior, as an open window, F. In the form of the device illustrated two such passages are shown one B leading from the lower part of the window and connected with a side of the canopy, in which a suitable 75 opening is of course made, the other C leading from the upper portion of the window and connected with the top of the canopy which may be of pyramidal or conical form as appears in the figures of the drawing. These passages are preferably constructed, as is canopy A, of cloth stretched over a light frame-work which may or may 80 not be collapsible just as desired depending upon whether the device is a more or less permanent fixture. As shown, the upper duct is of smaller diameter than the lower one and is connected with a suitable opening 85 in a board I inserted above the upper sash of the window. The outer end of the lower 90 passage is supported on two transverse rods R. Fig. 3, any unoccupied portion of the window frame being closed by a curtain S.

Provision for vertical adjustment of the canopy A over the bed and patient may be 95 easily effected by attaching cords N to the canopy and lower passage at points P P, respectively, and passing these cords through pulleys L hung at a suitable height above the bed. By means of these the canopy can 100 be conveniently raised when the patient so desires or to permit the attendant to arrange the bed.

The operation of my improved device is quite simple and should be evident from the 110

foregoing description of its construction. The outside air enters freely through one passage usually B into the canopied inclosure A within which the subject reclines, 5 and after circulating about him escapes through the other passage. This circulation is set up and maintained by the slight heating effect of the body of patient which warms the air sufficiently to cause the same 10 to seek to ascend. I would not be understood, however, to imply that a second duct like C, is essential to securing such circulation, for I have found that where the lower duct as B is of large enough cross-section it 15 will accommodate both an inflowing and out-flowing current of air. In other words, the provision of separate openings at different levels communicating with the exterior of the apartment taken in conjunction with the 20 heating effect of the body of the patient above referred to would suffice for establishing and maintaining the desired circulation.

By the use of my device, it is hence seen, all the advantages of sleeping out of doors, 25 lately so much emphasized by medical experts and others, are secured by the fresh air devotee while enjoying all the comforts and conveniences of a modern bed room, and without encountering the rigors attendant upon an unexpected rainfall or snow. The advantages of the use of a device of 30 this kind in hospitals and sanitaria where fresh air if procurable is frequently the best medicine, not only for the convalescent but also for the patient while still critically ill, are inestimable. It should be noted in 35 this connection that the circulation of air induced in the manner previously set up is gentle and partakes in no wise of the character of a draft such as is apt to prove disastrous to even the hardy person who ventures to sleep by an open window. The convenience with which my device, in the approved 40 form here shown, can be set up and handled will further commend it to the user.

Having thus described my invention in detail, that which I particularly point out and distinctly claim, is:—

1. A fresh-air-supply device for a sleeping 50 apartment, comprising an inclosure adapted to be supported over a bed or the like, the upper and lower portions of said inclosure having independent communication with the exterior of such apartment.

55 2. A fresh-air-supply device for a sleeping apartment, comprising an inclosure adapted to be supported over a bed or the like and connect the same with a window of such apartment, the upper and lower portions of 60 said inclosure communicating with corresponding sections of such window.

3. In a fresh-air-supply device for a sleeping apartment, the combination with an inclosed canopy adapted to be supported over 65 a bed or the like, a plurality of air passages

connecting said canopy with the exterior of such apartment and adapted simultaneously to conduct air to and from said canopy.

4. In a fresh-air-supply device for a sleeping apartment, the combination with an inclosed canopy adapted to be supported over a bed or the like, of air passages connecting said canopy with the exterior of such apartment, one of such passages being adapted to conduct air to said canopy and the other to 75 conduct air therefrom.

5. In a fresh-air-supply device for a sleeping apartment, the combination with an inclosed canopy adapted to be supported over a bed or the like, of two air passages connecting said canopy with the exterior of such apartment, one of said passages entering said canopy laterally and the other leading from the top thereof.

6. In a fresh-air-supply device for a sleeping apartment, the combination with an inclosed canopy comprising a suitable frame and a cover removably secured thereto and having a ruffle or apron about its lower edge, means adapted to adjustably support said canopy over a bed or the like, and air passages connecting said canopy with the exterior of such apartment, one of such passages being adapted to conduct air to said canopy and the other to conduct air therefrom.

7. In a fresh-air-supply device for a sleeping apartment, the combination of an inclosed canopy comprising a suitable frame and a cover removably secured thereto, said cover being provided with a ruffle or apron about its lower edge and with a flexible window in one of its sides, means adapted to adjustably support said canopy over a bed or the like, and air passages connecting said canopy with the exterior of such apartment, one of such passages being adapted to conduct air to said canopy and the other to conduct air therefrom.

8. In a fresh-air-supply device for a sleeping apartment, the combination with a window in such apartment, of an inclosed canopy comprising a suitable frame and a cover removably secured thereto, said cover being provided with a ruffle or apron about its lower edge and with a flexible window in one of its sides, means adapted to adjustably support said canopy over a bed or the like and to remove the same therefrom, a passage connecting one side of said canopy with the lower part of said window, the outer end of said passage being supported on transverse rods mounted in the window frame, and a second passage leading from the top of said canopy to the top of said window.

9. In a fresh-air-supply device for a sleeping apartment, the combination with a window in such apartment, of an inclosed canopy comprising a suitable frame and a cover removably secured thereto, said cover being provided with a ruffle or apron about its 120

lower edge and with a flexible window in one of its sides, means adapted to adjustably support said canopy over a bed or the like and to remove the same therefrom, a passage 5 connecting one side of said canopy with the lower part of said window, the outer end of said passage being supported on transverse rods mounted in the window frame, a curtain hung on said rods and adapted to close

the portion of said window unoccupied by 10 the end of said passage, and a second passage leading from the top of said canopy to the top of said window.

Signed by me, this 27th day of July, 1906.
FRANK S. LIPPITT.
